UNITED STATES PATENT OFFICE.

GEORGE W. DEAN, OF NEW YORK, ASSIGNOR OF ONE-HALF TO JAMES STEEL,
JR., OF BROOKLYN, N. Y.

MOUTH-PIECE FOR BAGS.

SPECIFICATION forming part of Letters Patent No. 400,194, dated March 26, 1889.

Application filed January 8, 1889. Serial No. 295,762. (Model.)

To all whom it may concern:

Be it known that I, GEORGE WASHINGTON DEAN, a citizen of the United States, residing in the city, county, and State of New York, 5 have invented certain new and useful Improvements in Mouth-Pieces for Bags, of which the following is a specification.

In Letters Patent of the United States No. 392,236, granted Philo O. Soper November 6, 1888, a mouth-piece for bags is shown consisting of two similar three-sided sections hinged together so as to open and close with facility, and which when closed is open only at the bottom, which is designed to fit into a bag. 15 When thus closed, the mouth-piece presents in cross-section, approximately, the form of an isosceles triangle, and the opposite sides of the sections come together at their upper edges. In this patent spiral springs attached 20 to the outside of the sections are employed for holding them together, so as to close the delivery-opening. Fastening devices consisting of a double ball-clasp of well-known construction are also there shown for connecting the 25 upper edges of the sides of the mouth-piece.

The object of my invention is to simplify and improve the construction of the mouth-piece shown in the above-named patent, more firmly connect the sections, more completely 30 close the delivery-opening at the top of the device, and provide an improved fastening or catch both simple in construction and easily manufactured, and so arranged that the sections of the bag mouth-piece may be held together without the use of springs.

In the accompanying drawings, illustrating my invention, Figure 1 is an end view of my improved mouth-piece for bags, showing the sections closed. Fig. 2 is a similar view showing the sections open. Fig. 3 is a plan view 40 of the device shown in Fig. 2. Fig. 4 shows the device applied to a tobacco-bag.

The mouth-piece, as shown in the drawings, is composed of two like sections, A B, formed 45 each with three sides, two sides, preferably the narrower ones, a or b , being of equal width and at right angles to the third side, a' or b' , and the sides a and b are hinged to each other at c in any suitable way, but preferably, as 50 indicated, by indenting the sides of the sec-

tions to interlock. In cross-section each section of the mouth-piece preferably presents the form of a rectangle with one of the sides removed. The hinged connections between the sides a and b of the respective sections 55 are located on lines drawn at right angles from the sides a' or b' at points at equal distances between their ends. The sides a b are cut away at an angle or bevel just below the hinges, as shown at z . Consequently, when 60 closed, the mouth-piece, as shown in Fig. 1, presents the approximate form of an isosceles triangle, the width of the sides a b being such that the distances from the hinge c to the apex and the faces of the triangle are about the 65 same. At points about midway of the length of the sides a' b' , but preferably slightly below lines perpendicular to said sides and running to the hinge, fingers d are formed, which constitute bearings or supports for the 70 strings for tying the mouth-piece to the bag. The pyramidal shape of the mouth-piece tends to prevent its withdrawal from the bag.

It will be noted that the side a' of the section A is provided with a lip or extension, a^2 , 75 which, when the mouth-piece is closed, extends above the edge of the side b' on the section B, and this lip or extension is provided with a catch, a^3 , preferably formed by making a burr with a suitable tool in the lip. The burr, slipping past the edge of the part b' , locks the bag-mouth sections together, and the mouth-piece is opened by forcing the sections apart against the tendency of the burr to hold them. The lip or extension a^2 insures a more perfect 85 closure of the mouth-piece, and also a guide over which the tobacco may be poured when the mouth-piece is fitted to the ordinary cloth tobacco-bag. It also affords a handle or thumb-piece by which the bag may be opened. 90 The extension or lip also enables me to form in a simple and efficient way a catch for holding the two sections of the mouth-piece together.

f indicates ears or projections formed on the 95 section b near its inner end under the hinge, and turned around the edge of and down upon the opposite section, a . By this construction the two sections are held more firmly together, especially when the hinge-connection 100

is such as that shown in the drawings. The projection also serves as a stop to limit the opening of the mouth-piece. All the parts of this device may be struck up out of sheet

5 metal at very small expense, only two blanks or pieces of sheet metal being employed.

In the Soper mouth-piece coil-springs are used, which more than double the expense, and in one form of the device the ball-clasp 10 is employed, which necessitates the soldering to the bag-piece sections of additional pieces of metal; but I omit the springs and the double ball-catch soldered on separately, and form the device in two pieces, as above ex- 15 plained.

I have shown my improvements applied to a form of mouth-piece for bags especially designed for containing tobacco; but my improvements may be employed on mouth-pieces 20 for bags differing from the specific kind in form and shape from that shown in the drawings.

Having thus described my improved mouth-piece for bags, what I claim as my invention 25 is—

1. The combination, substantially as hereinbefore set forth, in a bag mouth-piece of general triangular shape, of two like sections, $a a' b b'$, hinged to each other, one of the

sections having an extension or lip, a^2 , on the 30 upper edge of its middle portion, projecting beyond the corresponding edge of the opposite section.

2. The combination, substantially as hereinbefore set forth, in a bag mouth-piece of 35 general triangular shape, of two like three-sided sections, $a a' b b'$, hinged to each other, one of the sections having an extension or lip, a^2 , on the upper edge of its middle portion, projecting beyond the corresponding 40 edge of the opposite section, and a catch or fastening device formed on the lip.

3. The combination, substantially as hereinbefore set forth, in a bag mouth-piece of 45 general triangular shape, of two like sections hinged to each other and of rectangular shape in cross-section, each section being formed with an inclined edge, z , on each side and an ear or projection, f , on one section turned over the edge of the other section of the 50 mouth-piece.

In testimony whereof I have hereunto subscribed my name.

GEORGE W. DEAN.
